UNITED STATES PATENT OFFICE.

ROBERT COWEN, OF CAMBRIDGEPORT, MASSACHUSETTS.

DESIGN FOR A RUBBER SOLE.

SPECIFICATION forming part of Design No. 16,757, dated June 29, 1886.

Application filed February 19, 1886. Serial No. 192,598. Term of patent 7 years.

To all whom it may concern:

Be it known that I, ROBERT COWEN, a citizen of the United States, residing at Cambridgeport, county of Middlesex, and State of Massachusetts, have invented and produced a new and original Design for Rubber Soles, of which the following is a specification, reference being had to the accompanying drawing, forming part thereof.

10 My design consists of a rubber shoe sole and heel having pyramidal projections, upon which projections netting is represented, a lawn-tennis racket and one or more balls being arranged in relief in spaces unoccupied by the 15 projections and net, and constituting the main features of my design.

A plan view of my design is shown in the accompanying drawing. The sole is of usual shape. A racket, *a*, and balls *b* *h* are shown 20 in relief upon the tread and heel, respectively, the said racket and balls representing the racket and ball employed in the game of lawn-tennis. A number of pyramidal projections, *c*, cover the surface of the sole and heel, substantially as shown, and these projections have 25

upon them the representation of a netting in intaglio.

What I claim is—

1. In a design for rubber soles for shoes, the tread or sole proper, comprising the representation of a lawn-tennis racket, ball, and net, substantially as shown. 30

2. In a design for rubber soles for shoes, the heel, comprising the representation of a lawn-tennis net and ball, substantially as shown. 35

3. A design for rubber soles for shoes, consisting of the representations of a tennis ball and racket on the tread or sole, a tennis-ball on the heel, and a net and a series of pyramidal projections, over or upon which the aforementioned balls, racket, and net are arranged, substantially as shown. 40

In testimony whereof I have signed my name to this specification in the presence of two subscribing witnesses.

ROBERT COWEN.
